UNITED STATES PATENT OFFICE.

MAXWELL ALPERN, OF PHILADELPHIA, PENNSYLVANIA, ASSIGNOR TO AMERICAN ENGINEERING COMPANY, OF PHILADELPHIA, PENNSYLVANIA, A CORPORATION OF PENNSYLVANIA.

ASH CRUSHING AND DISCHARGING DEVICE.

1,182,728.

Specification of Letters Patent.

Patented May 9, 1916.

Application filed March 6, 1913. Serial No. 752,422.

To all whom it may concern:

Be it known that I, MAXWELL ALPERN, a citizen of the United States, residing in Philadelphia, Pennsylvania, have invented 5 certain Improvements in Ash Crushing and Discharging Devices, of which the following is a specification.

One object of my invention is to provide 10 a novel device for removing the ashes from boiler furnaces which are supplied with fuel by means of mechanical stokers, the arrangement of parts being such that the apparatus may be used either continuously or intermittently to crush and discharge the 15 ashes collecting at the rear of the stoker.

I further desire to provide an ash dis- 20 charging device which shall include a reciprocable member of peculiar form de- signed to co-act with a fixed abutment for the purpose of crushing large masses of ash or clinkers so as to cause their removal without interfering with the proper operation 25 of the furnace to which said device is attached; the invention contemplating novel means for permitting the discharge of the ash without material crushing if this should be desirable.

Another object of my invention is to pro- 30 vide a crushing and discharging device so designed as to maintain an air-excluding layer of ashes over its operating parts, the arrangement of the various parts preferably being such as to substantially reverse the direction of movement of the ashes so as to 35 keep the hot clinker away from the bridge wall, although where the clinker has a low fusing point, this change of movement is not necessary.

These objects and other advantageous 40 ends I secure as hereinafter set forth, reference being had to the accompanying drawings, in which,

Figure 1 is a side elevation, partly in 45 vertical section, illustrating the preferred form of my invention, and Fig. 2 is a plan of the apparatus shown in Fig. 1.

In the above drawings, 1 represents a portion 50 of the setting of a boiler or other furnace having a bridge wall 2. The dead plate or lowest portion of the fuel burning portion of the furnace is shown at 3 and the rear-most part of this is spaced away from the bridge wall or rear part of the furnace 2 to provide a deep transversely extending

cavity 4 for the reception of ashes dis- 55 charged from the top of the structure 3 in any of the ways well known in this art. Ex- tending transversely of the setting 1 in which they are mounted are two parallel channel sections or other supporting struc- 60 tures 5 and 6, on which are mounted bear- ings 7 and 8 for the two shafts 9 and 10. These latter carry rollers 11 designed to support a reciprocating crusher consisting of one or more sections 12, there being two 65 of said sections in the present instance.

As indicated in Fig. 2, each of the re- 70 ciprocating sections 12 has elongated re- cesses 13 forming tracks or guides for the reception of the supporting rollers 11 and the setting is cut away under the bridge 75 wall 2 in order to allow of the reciprocating sections being properly operated longitudinally of the furnace. Said sections have the form of a set of steps rising from the front 80 of the furnace toward the rear so that the riser portions 14 constitute crushing or pressure exerting faces, while the parts cor- responding to the treads of the step, serve to support the body of ashes.

Below the forward end of the reciprocating sections there is provided a trans- 85 versely extending edge supporting section 15 forming a fixed ash supporting surface upon which said forward ends of the crush- 90 ing members slide. The rear face of the dead plate structure 3 has mounted on it a transversely extending projecting plate 16 under which is mounted a transverse shaft 17 rotatably carrying a relatively fixed 95 abutment or crushing plate 18, there being in front of this plate a second transverse shaft 19 carrying a series of cams 20 which by proper adjustment of said second shaft 100 may be made to engage and support the abutment or plate 18. On the other hand said shaft 19 may be turned by suitable means so as to remove this support for the plate 18 and thereby permit it to swing to the front on the shaft 17 as an axis.

For reciprocating the crusher 12, any de- sired means may be employed, such for ex- ample, as a transverse shaft 21 mounted in suitable bearings carried by the stoker struc- 105 ture and provided with a series of arms 22, each connected by a link 23 with the movable crusher 12. In addition, the shaft 21 is pro- vided with another arm 24 connected

through a link 25 with a crank 26 which may be oscillated either continuously or intermittently as desired. Under operating conditions the stoker deposits a mass of 5 ashes in the cavity 4 and continuously adds to the same as fuel is burned in the furnace. The operation of the crank 26 causes oscillation of the shaft 21 and through the arms 22 and links 23 causes the crusher 12 to move 10 back and forth upon the rollers 11 at the bottom of the cavity 4. Assuming that the shaft 19 is maintained in the position shown in Fig. 1, with its cams 20 supporting or bearing against the fixed crushing plate 18, 15 every rearward movement of the member 12 allows a greater or less quantity of ash to move downwardly from in front of the plate 18 on to the fixed plate 15. As the crusher 12 is moved to the front, this mass of ashes 20 on the plate 15 is pushed off or discharged into any suitable receptacle, while the mass between the risers 14 of the crushing member 12 and the fixed plate 18 is crushed or compressed to such an extent that upon the 25 next rearward movement of said member 12, a greater or less quantity of the said material falls on to the plate 15 as before. As a consequence of this operation, it is obvious that any clinkers discharged into the cavity 30 4 are sooner or later crushed or broken between the crusher 12 and the plate 18 and are discharged in small pieces over the plate 15. At all times, however, there is a relatively deep mass of ashes to the rear of the 35 plate 18 and above the plate 15 within the cavity 4 so that the undesirable entrance of air to the furnace is very effectually prevented.

It is of course obvious that under certain 40 conditions of operation of the stoker it would not be necessary to continuously actuate the crusher 12 and it would therefore be used only when necessary to discharge the accumulated mass of ashes from the cavity 45 4. If for any reason it should be desired to remove the mass of ashes without crushing them and that at a higher speed than would ordinarily be advisable, the shaft 19 is so rotated as to release the high parts of 50 the cams 20 from the plate 18, thereby permitting this to swing forwardly under the action of the ashes propelled by the member 12. There is thus provided a relatively 55 large outlet from the cavity 4 through which the successive reciprocations of the member 12 quickly discharge all the ashes which may have accumulated.

It is to be understood that the position of 60 the plate 18 and hence the size of the opening between it and the adjacent part of the crusher 12 may be varied by means of the shaft 19 and cams 20 in order to suit the apparatus for operation with different types of stokers and for different kinds of fuel. 65 Obviously other means for adjusting the

plate 18 to vary the dimensions of the discharge opening may be employed in place of that shown, without departing from my invention.

It will be understood that it is immaterial 70 whether the structure 3 which carries the plate 16 and abutment 18 with their associated parts, is the wind box or the bridge wall; that is to say, while in the case illustrated, the ashes flow toward the reciprocatory sections 12 and have their direction of movement reversed thereby, they obviously may be delivered to the depression 4 from over the structure 2 in which case they naturally move toward the abutment 18 80 and are also forced toward it by the action of the sections 12. With such an arrangement, the part 2 would be the wind box and the structure 3 would be the bridge wall.

I claim:

1. A furnace, having a transversely extending ash receiving cavity; a transversely extending abutment plate mounted therein and having a substantially perpendicular face; a step-formed structure in the bottom 90 of the cavity having crushing faces substantially parallel with the face of the abutment plate; and means for moving said structure toward and from the plate to crush the ashes and thereafter discharge the same. 95

2. The combination in a furnace having a fuel burning portion, a bridge wall, and a cavity between said parts, of a step-formed structure adjacent the bridge wall and partially closing the bottom of said cavity; 100 means for movably supporting said structure; a substantially perpendicular abutment plate mounted in the cavity at the rear of the fuel burning portion of the furnace and extending above the lowest portion of 105 said step-formed structure; with means for moving said latter structure toward and from the abutment plate.

3. A furnace having a transversely extending ash receiving cavity; supporting 110 rollers mounted in said cavity with their axes in a substantially horizontal plane; a step-formed crusher having tracks engaging said rollers; means for reciprocating said crusher in a substantially horizontal 115 plane; and an abutment plate extending substantially parallel to the operative faces of said crusher.

4. A furnace having a dead plate structure; a bridge wall spaced away from the same to form an ash receiving cavity; an abutment plate mounted in said cavity below said dead plate; a crusher made in a series of sections having faces substantially parallel with the adjacent face of said plate; 125 rollers supporting said crusher; and means for moving said crusher in a horizontal plane toward and from the plate.

5. The combination in a furnace of a dead plate; a bridge wall spaced away from the 130

rear end of said plate to form a laterally elongated relatively deep perpendicular cavity; a horizontally movable step-formed structure having perpendicular faces forming the bottom of said cavity; a relatively heavy laterally elongated abutment plate carried by the rear end of the dead plate with its face in a vertical plane and with its lower edge terminating slightly above the bottom of the crusher to form a discharge

opening; with means for moving the crusher toward and from the abutment plate.

In testimony whereof, I have signed my name to this specification, in the presence of two subscribing witnesses.

MAXWELL ALPERN.
